UNITED STATES PATENT OFFICE

SIMON SIEGFRIED EGGER-HANSEN, OF VIENNA, AUSTRIA, ASSIGNOR TO EGGER-HANSEN'S NAAMLOOZE VENNOOTSCHAP TOT EXPLOITATIE VAN OCTROOIJEN, OF ROTTERDAM, NETHERLANDS

PRICE SCALES

Application filed June 29, 1926, Serial No. 119,443, and in Austria July 16, 1925.

This invention relates to a device for indicating the price, which can be fitted to scales already in use or can be built into new scales and which renders visible at both sides of the 5 scale the weight of the article put on the scales and the purchase-price corresponding to the indicated weight and the set base-price.

The known price-indicating devices, which 10 are visible at both sides, have the drawback, that it is not possible to read off the prices for each part of the weight and for each base-price, because the arrangement of all products of the parts of the weight for any desired 15 base-price would necessitate an indicating device of an impossibly large size. Therefore up to now in the arrangements with a cylindrical indicating drum or with scale-or dial strips the price is indicated only for a limited 20 number of kilogramme-base prices, for instance only for each fifth or tenth weight-mark on the dial, while prices between these weight-marks have to be determined by calculation.

25 According to the present invention these drawbacks are removed by guiding the dial strip and positioning the figures in a quite novel manner, whereby it is possible to make the device of small size and render clearly 30 visible at both sides of the device the prices for each weight of any desired base-price and thus produce price-scales, which satisfy all requirements.

35 A strip, band or tape, secured to two oppositely disposed rollers and passed over the same in the shape of a S-loop in such a manner that it can be wound up and off and furnished at both sides with suitable like 40 figure-columns, is positively operated by setting any desired base-price with the aid of a suitable chain-drive, wheel-drive or by a combination of both kinds of drives in such a manner, that the product resulting from the 45 adjusted base-price and the indicated weight, thus the buying or selling price of the weighed article, is visible automatically at both sides in corresponding sections.

50 Two modes of carrying out the present invention are illustrated by way of example on

the accompanying sheets of drawings in which—

Fig. 1 shows the device in front view partly in section, and

Fig. 2 illustrates the band and guide-rollers 55 in cross-section.

Figs. 3 and 4 show a modified embodiment according to the present invention.

In the construction illustrated in Figs. 1 and 2, a band *c*, which is provided at both 60 sides with the products of the weights (from 1 *dkg* to 100 *dkg*) with the basic prices (from 1 cent to 100 cents) passes over and is secured to two rollers *a* and *b*, the said band being fed in the shape of an inverted S-loop and 65 can be wound up and off on the said rollers. Toothed wheels *i*, *k*, *i'*, *l*, *m*, *n*, *o*, *p*, mounted on shafts *d*, *e*, *f*, *g*, *h*, are positively connected with one another at suitable ratios by means of driving chains *q*, *r*, *s*, *t*, so that by the operation of the handles *u* and *v*, which are mounted on the chains (bands) *s* and *t*, those 70 product-columns are automatically set for reading off, which correspond to the adjusted base-price carried out thereby. Thus through 75 the windows *w* and *x* will be visible the product resulting from the adjusted base-price and the indicated weight, and the selling- and purchasing price is immediately visible to the salesman and purchaser in the elongation of 80 the weight-indicator. The tensioning rods *z*, *z'*, *z''*, *z'''*, *z''''* serve for tensioning the band behind the windows and render possible a 85 flat indicating area of suitable size.

Example:—If the selling price for 1 kilogramme, thus the base-price of an article, amounts to \$3.20, the handle *u* has to be adjusted on the setting or adjusting chain to the Figure 3 and the handle *v* has to be shifted on the adjusting to the Figure 2. In consequence of the positive operation caused thereby, the rollers *a* and *b* are adjusted in such a manner, that in the weight scale opening appears the number 320 and in the other window all products of 320 with the ordinary figure-system, thus in the elongation of the weight-pointer there appears at the corresponding place in the window the product resulting from the indicated weight and the 95 base-price 320, e. g. the purchasing price. 100

A re-setting to zero is not necessary when changing the base-price, because the arrangement permits of the desired adjustment of the two handles either up or down to the required figure value of the base-price. The band cannot break owing to the arrangement of a suitable locking device.

In the construction illustrated in Figs. 3 and 4, two bands 10, 10^a are employed, each band being provided at one side with the products of the weights (from 1 *dkg* to 100 *dkg*) and the basic prices (from 1 cent to 100). Each band passes over and is secured to two pairs of rollers 11, 11^a and 12, 12^a respectively and can be wound on and off of said rollers, the said bands passing over tensioning rollers 13, 13^a, 14, 14^a respectively, and offering a plain reading surface of sufficiently large size.

These pairs of rollers are adjustable in a suitable ratio by means of the toothed wheels 15, 16 and 17 and by the driving chain 18 passing over the ratio-wheel 19 and over the driving wheel 20, so that on actuating the handle 21 mounted on the wheel 20, the pairs of rollers and their product-columns for each desired base-price are set which now becomes automatically visible at both sides in the opening "kg". The products of the weights in the window *si*, corresponding to the base-price in kilogrammes now adjusted, may be indicated by suitable means, such as an adjustable pointer 22 cooperating with the scale 23.

It is not necessary to fit the described price-indicator in a scale or to mount the same on a scale, it can be used as an independent price-indicating device for any desired scales, if the same is disposed at the side of the latter. In this case the same is provided with weight-dials above or below the two sections at which the price is visible. In this event, after setting the base-price, that number indicates the selling price, corresponding to the weight of the article put on the scales, which appears below or above that mark of the weight-dial.

Having now particularly described and ascertained the nature of my said invention and in what manner the same is to be performed, I declare that what I claim is—

1. A computing device comprising a casing having a window therein, a pair of drums, an indicia carrying band having its end portions wound on said drums, respectively, for adjustment by rotation of said drums to have different portions thereof exposed to view through said window, and two separate endless chain devices one operatively connected with the band and the other operatively connected with the first-mentioned chain device to impart unit and fractional rotary adjustments to said drums, respectively.

2. A computing device comprising a casing having a window therein, a pair of drums,

an indicia carrying band having its end portions wound on said drums, respectively, for adjustment by rotation of said drums to have different portions thereof exposed to view through said window, a band adjusting device in the form of an endless chain operatively connected with said drums and movable a predetermined amount to impart a predetermined amount of rotary adjustment to said drums, and another band operating device in the form of an endless chain operatively connected with said first mentioned chain and movable a greater amount than said first mentioned chain to impart the same predetermined amount of rotary adjustment to said drums.

3. A computing device comprising a scale element, an endless chain geared to said scale element for imparting unitary adjustments thereto, and a second endless chain geared to said first mentioned chain and operable through the latter to impart fractional adjustments to said scale.

In testimony whereof I have signed my name to this specification.

SIMON SIEGFRIED EGGER-HANSEN.
